UNITED STATES PATENT OFFICE.

JOSEPH MORWITZ, OF PHILADELPHIA, PENNSYLVANIA.

REGULATOR OF TEMPERATURE OF APARTMENTS.

SPECIFICATION forming part of Letters Patent No. 309,728, dated December 23, 1884.

Application filed February 6, 1884. (No model.)

To all whom it may concern:

Be it known that I, JOSEPH MORWITZ, a citizen of the United States, residing in the city and county of Philadelphia, State of Pennsylvania, have invented a new and useful Improvement in Regulators of Temperature of Apartments, which improvement is fully set forth in the following specification and accompanying drawings, in which—

10 Figure 1 is a side elevation of a regulator embodying my invention. Fig. 2 is a longitudinal section thereof enlarged.

Similar letters of reference indicate corresponding parts in the two figures.

15 My invention consists of a thermostat for automatically regulating the temperature of an apartment by the changes of temperature therein, the construction and operation being hereinafter fully set forth.

20 Referring to the drawings, A represents a vessel, preferably of glass, and consisting of a longitudinally-extending tube, A', having at its ends upwardly-projecting limbs B B', which communicate with said tube.

25 C represents a vertical tube, which projects into the limb B, and has its lower end above the level of the tube A', said tube C being tightly fitted to the top wall of the limb B. Mercury is introduced into the limb

30 B' through a spout, a, attached thereto, or through the tube C, so as to entirely fill the tube A' and the limbs B B' to a level just above the upper wall of said tube. A quantity of sulphuric ether is then poured into

35 the limb B through the tube C, the mercury in said limb acting as a seal to prevent the ether passing into the other limb, B'. An additional quantity of mercury is then introduced into the limb B', so as to rise therein

40 above the bottom of the tube C, thus sealing said bottom and confining the ether in the limb B above the mercury therein, the upper end of the tube C being securely closed by a plug or stopper, C', whereby as the lower end

45 dips into the mercury the vapor is confined air-tight in the limb B. The vessel A is mounted on a bracket, D, suitably supported

within an apartment, and has fastened to it a balancing-arm, E, one end whereof is at-

50 tached by means of a pivoted connection, F, to a rod or bar, G, whose ends are secured to registers or dampers H H', the register

H being that of the hot-air inlet of the apartment, and the register H' that of the outlet of the air or ventilator of the apartment. 55 It will be seen that the balance or poise J of the arm E is set relatively to the desired temperature of the apartment. When the temperature increases, the vapor of air and ether contained in the link B, warmed by the increased temperature, expands and exerts its pressure on the mercury on the limb B, and forces it therefrom and from the tube A' into the limb B', whereby the latter limb becoming heavy overcomes the balance of the tube, 60 and thus tilts the vessel and the connected arm E in such manner as to operate the rod G, whereby the register H is closed and the register H' opened, thus controlling the admission of hot air into the apartment and 70 permitting the escape of the existing air therefrom. As soon as the required temperature is restored the vapor in the limb B contracts or condenses, and the excess of mercury in the limb B' is permitted to return to the limb 75 B, thus balancing the vessel, whereby the rod G is operated to reopen the hot-air register and close the upper register or ventilator. Of course slight changes of temperature of the apartment may operate the registers H 80 H' to a partial extent, and thus an equable temperature may be maintained.

It is evident that cold air may be admitted to the apartment through the register H, the flue thereof communicating with a supply of 85 fresh cold air, instead of a hot-air chamber or heater. In this case the vessel A may be balanced to operate the cold-air register and the upper register or ventilator relatively to the temperature desired in the apartment, and 90 it is also evident that by proper connection of the rod G with the registers the latter may be simultaneously closed or opened, as desired, or the rod G may be connected with the door or doors and the damper of a furnace, so as to 95 regulate the heat thereof.

I do not claim, broadly, a balanced vessel containing mercury for automatically operating a damper.

Having thus described my invention, what 100 I claim as new, and desire to secure by Letters Patent, is—

1. In an automatic regulator for dampers, a balanced vessel consisting of a tube having

- limbs at both ends, with mercury in both the tube and limbs, one of the said limbs being provided with a tube placed within it, said interior of tube having the plane of its lower 5 end below the level of the mercury contained in the inclosing-limb, substantially as and for the purpose set forth.
2. A vessel consisting of a tube with limbs at its ends, with mercury in both tube and 10 limbs, a tube fitted in one of the limbs dipping into the mercury at its lower end and closed at top, said limb containing also expansible vapor above the column of mercury,

and connections with a register of an apartment, said parts being combined and operating substantially as and for the purpose set forth. 15

3. The vessel A, constructed as described, support D, balancing-arm E, rods G and F, and registers H H', combined and operating substantially as and for the purpose set forth. 20

JOSEPH MORWITZ.
